UNITED STATES PATENT OFFICE.

GOTTFRIED WESTPHAL, OF BROOKLYN, NEW YORK.

DESIGN FOR A TRANSLUCENT BOWL.

46,712.

Specification for Design.

Patented Nov. 24, 1914.

Application filed September 8, 1914. Serial No. 860,816. Term of patent 3½ years.

To all whom it may concern:

Be it known that I, GOTTFRIED WESTPHAL, a citizen of the United States, residing at Brooklyn, in the county of Kings and State of New York, have invented a new, original, and ornamental Design for Translucent Bowls for Semidirect Lighting, of which the following is a specification, reference being had to the accompanying drawing, forming part thereof.

The figure is a side elevation of the bowl.

I claim:

The ornamental design for a translucent bowl for semi-direct lighting, as shown.

GOTTFRIED WESTPHAL.

Witnesses:

F. D. AMMEN,
A. DE MOTT.
